CLAIM

The ornamental design for a scanner frame, as shown and described.

DESCRIPTION

FIG. 1 is a rear perspective view of a scanner frame with a display device shown therein for environmental purposes, in accordance with my new design;

FIG. 2 is a bottom plan view of the scanner frame in accordance with my new design;

FIG. 3 is a front right perspective view of the scanner frame with the display device shown therein for environmental purposes, in accordance with my new design;

FIG. 4 is a front left perspective view of the scanner frame in accordance with my new design; and,

FIG. 5 is a front right perspective view thereof.

The broken lines show environmental structure that forms no part of the claim designed.
